UNITED STATES PATENT OFFICE

94,108

DESIGN FOR A SHOE

Albert F. Bancroft, Newton, Mass., assignor to
Bancroft Walker Co., Waltham, Mass., a cor-
poration of Massachusetts

Application July 12, 1934, Serial No. 52,547

Term of patent 3½ years

To all whom it may concern:

Be it known that I, Albert F. Bancroft, a citizen of the United States, residing at Newton, in the county of Middlesex and State of Mass., have invented a new, original, and ornamental Design for a Shoe, of which the following is a specification, reference being had to the accompanying drawing, forming a part thereof, in which

Fig. 1 is a plan view of a shoe showing my new design, and

Fig. 2 is a view of the shoe in side elevation, in both views the outline of the shoe being conventional and shown in dot and dash lines.

The ornamental effect of my design resides in the following features, viz., a small triangular fox-

ing overlying the vamp with its apex extending toward the tip and its base adjacent to the edge of the throat of the vamp, and a continuous and conspicuous seam extending from said triangular foxing outwardly on both sides, then rearwardly and outwardly in diverging relation to the upper margin of the vamp and in a reverse curve to the sole on both sides of the shoe.

I claim:

The ornamental design for a shoe substantially as shown and described.

In testimony whereof, I have affixed my signature hereto.

ALBERT F. BANCROFT.
